UNITED STATES PATENT OFFICE.

FRANK A. VEDUTIS, OF MILLBURN, NEW JERSEY.

DESIGN FOR A SHOVEL.

60,115.

Specification for Design. Patented Dec. 27, 1921.

Application filed March 5, 1921. Serial No. 450,101. Term of patent 14 years.

To all whom it may concern:

Be it known that I, FRANK A. VEDUTIS, a citizen of Russia, and a resident of Millburn, in the county of Essex and State of New Jersey, have invented a new, original, and ornamental Design for a Shovel, of which the following is a specification, reference being had to the accompanying drawing, forming part thereof, in which—

Figure 1 is a perspective view of the shovel.

Fig. 2 is a top plan view thereof.

Fig. 3 is a bottom plan view of the same.

I claim:

The ornamental design for a shovel, substantially as shown.

FRANK A. VEDUTIS.
